DESIGN FOR A FACEPIECE FOR BREATHING APPARATUS

Daniel A. Green, North Braddock Township, Allegheny County, and Carey B. Jackson, Forest Hills, Pa.

Application December 4, 1940, Serial No. 97,062

Term of patent 14 years

To all whom it may concern:

Be it known that we, Daniel A. Green and Carey B. Jackson, citizens of the United States, residing at North Braddock Township and Forest Hills, respectively, in the county of Allegheny and State of Pennsylvania, have invented a new, original, and ornamental Design for a Facepiece for Breathing Apparatus, of which the following is a specification, reference being had to the accompanying drawing, forming a part thereof.

Fig. 1 is a front elevational view of a facepiece for breathing apparatus embodying our new design;

Fig. 2 is a top plan view thereof; and

Fig. 3 is a rear elevational view thereof.

We claim:

The ornamental design for a facepiece for breathing apparatus, substantially as shown.

DANIEL A. GREEN.
CAREY B. JACKSON.
